(57) **CLAIM**

The ornamental design for an instrument for measuring,
controlling, and testing optical lenses, as shown.

DESCRIPTION

FIG. 1 is a front, top, and left side, perspective view of an
instrument for measuring, controlling, and testing optical
lenses according to my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines immediately adjacent to the shaded areas
depict the bounds of the claimed design, while all other
broken lines are directed to environment. The broken lines
form no part of the claimed design.
